ATTORNEY.

UNITED STATES PATENT OFFICE.

GEORGE A. MOHR, OF DETROIT, MICHIGAN.

TESTING DEVICE FOR CORED CASTINGS.

Application filed October 21, 1926. Serial No. 143,030.

This invention aims to provide a testing device for cored castings by the use of which it can be quickly ascertained if there is a projecting fin or any other partial or complete stoppage in any passage which extends through a casting, for in many cases the passages are tortuous and it is impossible to make a visual inspection.

Another object of the invention is to provide a testing device which can be quickly mounted on a cored casting so that the latter may be tested before it has been machined to any great extent, and in many cases before any machining whatever has been done thereon, so as to eliminate the necessity of expending time and labor on castings which, when tested, may be found defective.

A further object of the invention is to provide a testing device in which compressed air may be employed, since the latter does not cause the cored walls and other parts of the casting with which it comes in contact to rust as is the case when water is employed for this purpose.

Having thus briefly outlined the major purposes of the invention I will now proceed to describe an embodiment thereof and illustrate its application with the aid of the accompanying drawings, in which:

Figure 1 depicts a sectional elevation of the invention;

Figure 2 is a side elevation showing one method of attaching the invention to a casting to be tested.

Figure 3 shows another view of the invention attached in another way to a casting the cored passages through which are also indicated.

Referring to the drawings, 1 designates a tubular member having a passage 2 extending longitudinally therein from its end 3 for the major portion of its length. An opening 4, smaller than and substantially concentric with, the passage 2 extends from the opposite end 5 of the member to the said passage. A nozzle 6 is slidably mounted through the opening 4 so that its discharge end 7 may be set to project any desired distance within the passage 2 for purposes hereinafter set forth. In the side of that portion of the tubular member through which the opening 4 extends a radial tapped hole 8 is provided for a set screw 9, by which latter the nozzle may be held against acci-

dental longitudinal movement through the opening 4.

On the outer end of the nozzle a valve 10 is usually provided, and into the opposite end of the valve a length of pipe 11 is secured. The pipe is in turn preferably connected by a flexible hose 12 to a source of air supply.

Integral with the tubular member 1 is a lateral connection 13 the centre line of which is inclined at less than ninety degrees to the nozzle 6 which does not usually extend past the said connection. The latter is usually threaded to receive the inner end of the cylinder 14 on the outer end of which a cover 15 having a central opening 16 therethrough is secured. An annular disc 17 is fixed, usually welded, in the inner end of the cylinder and forms a stop for the downward annular flange 18 integral with the plunger 19, so that the under surface of the latter cannot come directly in contact with the disc. Secured to the plunger is an outwardly extending indicating rod 20 which is of such length that it will, at all positions of the plunger, project through the opening 16 in the cap 15. In order to protect the indicating rod from becoming bent or damaged a shield 21, sometimes integral with the cap 15, is mounted on the latter.

In Figure 2 it will be seen that the end 3 of the tubular member 1, which is threaded externally, has a coupling 22 thereon, the opposite end of which latter is screwed onto a casting 23 so that the cored passage 24 in the latter registers with the passage 2 of the device.

In Figure 3 a connection 22^a is shown in threaded engagement with the end 3 of the tubular member 1. This connection has forwardly and inwardly extending lugs 22^b through which set screws 22^c are arranged so as to force the flange 23^b of the casting 23^a against the outer face of the said connection. In this case I usually insert a resilient washer 25 between the connection 22^a and the flange 23^b so as to insure a tight joint. When the device is mounted in position care should be taken to see that the passage 3 registers with the cored passage 24^a.

The operation of the device is as follows:

Compressed air passes through the nozzle 6 into the passage 2 and induces suction through the latter connection 13 thereby drawing the plunger 19 and its rod 20 in-

wards. When once the amount of air flow has been set, and the end 7 of the nozzle 6 moved longitudinally so that the suction will draw the plunger towards the disc 17, it will be found that the rod will be drawn inwards substantially a similar amount for all castings made from a similar pattern. But if there is a fin, such as the one indicated at 24^b, in the cored passage 24^a a disturbed air condition will result so that the rod 20 will move rapidly in and out, or if the cored passage is partly obstructed by an inward projection as shown at 24^c the air flow will be retarded, with the result that the rod will 10 not be drawn inwards as far as usual, and also if the projection is irregular enough to cause an air disturbance the rod will also move in and out.

Obviously the nozzle 6 must be differently set for different castings as there is a greater resistance to the air flow in castings having longer and more tortuous passages.

From the foregoing description it is believed that the construction and operation of the device will be readily understood. Moreover whereas a preferred construction of the invention has been described and shown it is understood that modifications may be made thereto provided they fall within the scope of the appended claims.

What I claim as my invention and desire to secure by Letters Patent is:

1. In a testing device for cored castings, the combination of a tubular member having a longitudinal passage therein, a nozzle extending into said passage substantially in line with the latter, a lateral inclined branch opening into said passage, a plunger in said branch, and an indicating means connected to said plunger adapted to function when fluid under pressure passes successively through said nozzle and passage.

2. In a testing device for cored castings, the combination of a tubular member having a longitudinal passage therethrough of reduced diameter at one end, a nozzle extending through said passage portion of reduced diameter, a lateral branch opening into said passage, a plunger in said branch, and an indicating rod connected to said plunger.

3. In a testing device for cored castings, the combination of a tubular member having a longitudinal passage therethrough or reduced diameter at one end, a nozzle slideable in said passage portion of reduced

diameter and extending therethrough, means for holding said nozzle in a predetermined position in said reduced passage portion, an inclined lateral branch opening in said passage, a plunger in said branch, and an outwardly projecting indicating rod on said plunger adapted to move when fluid under pressure passes successively through said nozzle and passage.

4. In a testing device for cored castings, the combination of a tubular member having a longitudinal passage therein, a nozzle extending into said passage substantially in line with the latter, a lateral inclined branch opening into said passage, an outwardly projecting cylinder mounted in said branch having its lower end in communication with the latter, a plunger in said cylinder, and an indicating rod extending outwardly from said plunger.

5. In a testing device for cored castings the combination of a tubular member having a longitudinal passage extending from one end, a nozzle extending into said passage substantially in line with the latter, an inclined lateral branch opening into said passage, a plunger in said branch, an indicating rod projecting outwardly from said plunger, said tubular member being adapted to be secured to a casting having a hole therethrough so that said passage registers with said hole, and said plunger being adapted to be drawn inwards when fluid under pressure passes successively through said nozzle, said passage, and said hole.

6. In a testing device for cored castings, the combination of a tubular member having a longitudinal passage therethrough of reduced diameter at one end, a nozzle extending through said passage portion of reduced diameter, an inclined lateral branch opening into said passage, a cylinder extending outwardly from said branch, said cylinder having its underside in communication with said branch, a plunger in said cylinder, an indicating rod on said plunger, said plunger being adapted to be drawn inwards in said cylinder by suction when fluid under pressure passes through said nozzle and said passage, means for regulating the amount of suction exerted on said plunger, and said tubular member being adapted to be secured to a casting having a hole therethrough so that said passage registers with said hole.

GEORGE A. MOHR.
